UNITED STATES PATENT OFFICE

2,611,375

COMBINED EYELASH BRUSH AND COMB HOLDER

Olive Grim Bablon, New York, N. Y.

Application March 9, 1950, Serial No. 148,601

6 Claims. (Cl. 132—19)

1

This invention relates generally to combined brush and comb holders and in particular to an eye-lash brush and comb holder wherein the brush and comb are individually removable therefrom.

The invention is particularly adaptable to the application of mascara or oil on eyelashes. Heretofore, conventional means for applying mascara or oil resulted in the coated eyelashes adhering one to the other, which introduced discomfort in addition to marring the appearance thereof. While the instant device is similarly employed, the function and results therefrom are vastly superior to those obtained by the aforementioned means.

The brush may be used to apply the mascara or oil and simultaneously the comb separates the coated eyelashes thus avoiding the undesirable adhesion.

Likewise the brush and/or comb may be readily removed from the holder, washed and reused or the said brush and comb may be replaced with others and so provide as desired brushes or combs for each particular need.

Therefore, the principal object of the invention resides in the provision of a novel combined eyelash brush, comb and holder.

Another object provides for an eyelash brush, comb and holder wherein the brush and/or comb may be readily removed from the holder for cleaning purposes or for the replacement thereof.

Still another object provides for a novel brush and comb holder which may be of simple construction and be inexpensively manufactured.

Other ancillary objects will be apparent henceforth from the detailed description when read in the light of the drawings, in which

Fig. 1 is a plan view of the invention illustrating the preferred sequence of assembly.

Fig. 2 is a sectional elevation taken on line 40 2—2 of Fig. 1.

Fig. 3 is a perspective view of a holder.

Fig. 4 is a perspective view of a brush.

Fig. 5 is a perspective view of a comb.

Fig. 6 is a fragmentary perspective view of a 45 second embodiment of the invention.

Fig. 7 is a fragmentary perspective view of a further embodiment.

Referring to Figs. 1 and 2, the invention appertains to a holder 10, a frame 11 therefor, preferably formed to wire or the like and which has a loop 12 formed in the lower extremity thereof. The loop 12 is of no particular size other than being sufficient to permit the insertion of a finger therein. The upper portion of the frame 11

2

terminates in two diverging arms 13, and 14 to which the holder 10 is secured by soldering, crimping or any other convenient means.

The holder 10 is formed from relatively thin sheet metal or the like, in the shape of an arc analogous to the natural arcuate positioning of eyelashes and has the ends 15, 16 thereof bent over to provide for the insertion of the frame arms 13, 14 in the recesses formed thereby. Subsequent soldering or crimping of the relative parts results in the permanent attachment of the frame 11 to the holder 10.

As shown in Fig. 3, plural punchings are formed in the holder 10 to provide resilient clamps 17 in the face thereof and resilient clamps 18 in the rear thereof. Adapted to be positioned adjacent holder 10 and retained thereon by clamps 17 or 18, are the brush 20, Fig. 4 and the comb 21, Fig. 5.

While in Figs. 1 and 2, the brush 20 is shown on the inside of the holder 10 and the comb 21 on the outside thereof, the respective brush and comb may be alternately positioned as required. Likewise, two brushes or two combs or a brush alone or comb alone could be utilized in the novel holder.

Another embodiment of the invention is illustrated in Fig. 6 wherein, a stamping 25 is formed to provide plural slots 26 and a sleeve 30 30 27. The said sleeve is arranged to receive the arm 13 therein and the slots 26 form clamps which receive the brush 20 and comb 21 therein. A like member 25, not shown, is provided for the arm 14 and the said brush and comb are supported therebetween with the compression-tension of the two arms 13, 14 retaining the brush and comb in effective position.

A further embodiment is disclosed in Fig. 7 wherein plural stampings 30 are provided with sleeves 31 for the insertion of arms 13, 14 respectively therein. Rectangular apertures 32 are formed to receive the ends 33 of the respective brush 20 and comb 21. As aforementioned the compression-tension of arms 13, 14 retain the brush and comb in cooperative relationship.

Briefly, the above novel holder may be adapted for many uses and may be applied to fill any particular need, and is especially directed toward the applying of oil or mascara to eyelashes and during the same operation separating the adhering eyelashes.

The brush 20 and the comb 21 have been designed with a view toward relatively inexpensive manufacturing costs in order that they be ex-

pendable and readily replaceable, with the holder therefor continually being utilized.

While three forms or embodiments of the invention have been shown and described herein for illustrative purposes, and the construction and arrangement incidental to three specific applications thereof have been disclosed and discussed in detail, it is to be understood that the invention is limited neither to the mere details or relative arrangement of parts, nor to its specific embodiments shown herein, but that extensive deviations from the illustrated forms or embodiments of the invention may be made without departing from the principles thereof.

In which I claim:

1. A combined eyelash brush and comb of the character described comprising a frame formed to provide gripping means and having plural diverging arms extending therefrom, an arcuate holder, means for securing said holder to said arms, plural punchings formed to provide clamps on both sides of said holder, an arcuate comb arranged to be secured in some of said clamps and an arcuate brush arranged to be secured in the remainder of said clamps.

2. A combined eyelash brush and comb of the character described comprising a wire frame having a body portion and a loop at one end thereof, the other end terminating in plural diverging arms, an arcuate holder, means for securing said holder to said arms, plural punchings formed to provide clamps on both sides of said holder, an arcuate comb arranged to be secured in some of said clamps and an arcuate brush arranged to be secured in the remainder of said clamps.

3. A combined eyelash brush and comb of the character described comprising a wire frame having a body portion and a loop formed at one end thereof, the other end terminating in plural diverging arms, an arcuate holder having the end portions thereof formed to provide apertures, means for securing said arms within said apertures, plural punchings formed to provide clamps on both sides of said holder, an arcuate

5

comb arranged to be secured in some of said clamps and an arcuate brush arranged to be secured in the remainder of said clamps.

4. A combined eyelash brush and comb of the character described comprising a wire frame having a body portion and a loop formed at one end thereof, the other end terminating in plural diverging arms, an arcuate holder having the end portions thereof formed to provide apertures, said holder arranged to be secured to said arms by crimping thereof, plural punchings formed to provide clamps on both sides of said holder, an arcuate comb arranged to be secured in some of said clamps and an arcuate brush arranged to be secured in the remainder of said clamps.

5. A combined eyelash brush and comb of the character described comprising a frame formed to provide gripping means and having plural diverging arms extending therefrom, an arcuate holder, means for securing said holder to said arms, an arcuate brush member, an arcuate comb member, and means for detachably securing said brush and comb members to said holder.

6. A combined eyelash brush and comb of the character described comprising a frame formed to provide gripping means and having plural diverging arms extending therefrom, an arcuate holder, means for securing said holder to said arms, plural punchings formed to provide clamps in the face of said holder, similar plural punchings formed to provide clamps in the rear of said holder offset relative to the former clamps, and said clamps arranged to receive arcuate comb members therein.
